Brooklyn, N. Y.

Application December 9, 1936, Serial No. 115,016

3 Claims. (Cl. 229—17)

This invention relates to paper receptacles or cartons and more particularly to such receptacles or cartons formed from a single blank, cut, shaped, dimensioned and folded to provide a carton of a suitable size formed of destructible material so as to be destroyed as found desirable after use.

An object of the present invention is to provide a carton of this character particularly designed for use in the vending of milk, cream or the like.

More particularly the invention is concerned in the provision of a paper carton or receptacle having an improved closure means associated therewith.

The invention together with its objects and advantages will be best understood from a study of the following description taken in connection with the accompanying drawing wherein:—

Figure 1 is a fragmentary plan view of a blank from which the carton is formed.

Figure 2 is a top plan view of the carton.

Figure 3 is a sectional view taken substantially on the line 3—3 of Figure 2 and

Figure 4 is a perspective view of the completed carton.

Referring to the drawing by reference numerals it will be seen that the carton is formed from a single blank cut, shaped, dimensioned and folded on lines 5 to provide four walls 6. At the lower end of the blank the latter is slit on lines in alignment with the fold lines 5 to provide a plurality of flaps for each of the walls 6 and these flaps are folded inwardly one upon the other to provide a multi-ply bottom wall 7 for the carton.

Also, and as shown in Figure 1 the upper portion of the blank is slit on lines 8 and folded on lines 9 to provide a plurality of super-imposed top wall forming flaps consisting of three flaps 10 folded in super-imposed relation and adhesively or otherwise positively united together to form a top wall 11 for the carton, as well as a cover flap 12 which latter adjacent the fold line 9 has a portion thereof adhesively united to the uppermost flap 10, and is creased as at 13 so that the flap 12 may be readily swung to open or closed position.

The flaps 10 are provided with openings 14 which in the present instance are shown somewhat diamond-shaped being rounded at the four corners of the diamond and which align as shown in Figure 3 to provide a pouring opening through the top wall 11 for the carton.

The outermost flap 12 has the center portion thereof pressed inwardly to provide at the inner or under side thereof a hollow cup-shaped yielding formation or plug 15 of an edge contour corresponding to the edge contours of the openings

14 so as to be pressed through said aligned openings for completely sealing or closing the top wall 11 of the carton.

In this connection, and as best shown in Figure 3 the peripheral wall of the plug or formation 15 is pressed outwardly as at 16 to provide an external continuous rib which engages the innermost flap 10 about the edge of its opening 14 so as to insure a positive retention of the cover flap 12 in closed position. (See Figure 3.)

The formation or plug 15 being hollow it will be apparent that the same will contract when an upward pull is exerted on the flap 12 so as to permit the plug or formation 15 to be drawn through the aligned openings 14 to effect an opening of 15 the carton at the top thereof.

From the above, it will be seen that a carton embodying the features of the present invention can be cheaply and economically made and at the same time may be provided with a positive and efficient closure means which will serve to substantially seal the carton and which at the same time is positively retained in closed position so as not to be easily displaced by the weight of the contents of the carton in the event, for example, the carton should become inverted.

It is thought that a clear understanding of the construction, utility and advantages of an invention of this character will be had without a more detailed description.

Having thus described the invention what is claimed as new is:—

1. A carton of the class described constructed of a folded blank having walls provided at their upper ends with flaps adapted to be folded in super-imposed relation to provide a top wall for the carton, three of said flaps being provided with apertures coinciding to define a single pouring opening for the carton and a fourth one of said flaps being provided on its under side with a formation defining a plug adapted to seat within the pouring opening for closing the carton, said fourth flap inwardly from one edge thereof being foldable on an imaginary transverse fold line, and between said fold line and said one edge thereof being adhesively united to the uppermost one of said three flaps and functioning as a hinged mounting for said fourth flap.

2. A carton of the class described constructed of a folded blank and having walls provided at their upper ends with flaps adapted to be arranged in super-imposed relation to provide a top wall for the carton, three of said flaps being positively united together and provided with coinciding apertures to define a single pouring open-

ing for the carton, and a fourth one of said flaps being foldable relative to the other of the flaps and being provided with a pressed out center portion defining a flexible plug-like formation adapted to seat within the pouring opening for closing the carton, said fourth flap inwardly from one edge thereof being foldable on an imaginary transverse fold line, and between said fold line and said one edge thereof being adhesively united to the uppermost one of said three flaps and functioning as a hinged mounting for said fourth flap.

3. A carton of the class described constructed of a folded blank and having walls provided at their upper ends with flaps adapted to be arranged in super-imposed relation to provide a top wall for the carton, three of said flaps being positively united together and provided with coinciding apertures to define a single pouring opening for the carton, and a fourth one of said flaps being

foldable relative to the other of the flaps and being provided with a pressed out center portion defining a flexible plug-like formation adapted to seat within the pouring opening for closing the carton, said pressed out plug formation having a continuous bead pressed out from the periphery thereof to engage the innermost one of said flaps at the end of the pouring opening for releasably securing the formation within the pouring opening and the fourth one of said flaps in folded superimposed relation on the uppermost one of said three flaps, said fourth flap inwardly from one edge thereof being foldable on an imaginary transverse fold line, and between said fold line and said one edge thereof being adhesively united to the uppermost one of said three flaps and functioning as a hinged mounting for said fourth flap.
